Primary Examiner — Cathron C Brooks*Assistant Examiner* — Katrina N Gonzalez(74) *Attorney, Agent, or Firm* — H.C. Park & Associates,
PLC(57) **CLAIM**The ornamental design for a door bell, as shown and
described.

DESCRIPTION

FIG. 1 is a front perspective view of the door bell;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
The broken lines illustrate portions of the door bell that form
no part of the claimed design.**1 Claim, 6 Drawing Sheets**(56)
